UNITED STATES PATENT OFFICE.

STEPHEN HAINES PLUM, 2d, OF MADISON, NEW JERSEY, ASSIGNOR TO AMERICAN TYPE FOUNDERS COMPANY, A CORPORATION OF NEW JERSEY.

FACSIMILE-PRINTING ATTACHMENT.

Application filed January 8, 1926. Serial No. 79,921.

This invention relates to an attachment adapted to be used in connection with a printing press for printing facsimile letters and other matter.

5 The object of the invention is to provide a facsimile printing attachment in the form of a separate complete unit or device which may be readily attached to a printing press of the Gordon type without requiring any 10 change in the press itself.

It is a further object of the invention to embody in the attachment certain novel features of construction having in view the production of a relatively inexpensive device 15 adapted to be manufactured and shipped complete, and readily attached and operated by the printer without requiring special skill or tools.

Facsimile letters are produced on a Gordon type press by interposing a sheet of suitable fabric between the form and the platen. In some instances it is done by affixing a 20 sheet of fabric to the usual platen grippers. The fabric, however, soon wears out due to 25 the tearing of the fibres or threads caused by the continued impact of the type on the same spots in the fabric.

This invention includes in its features the 30 interposition of a fabric which is automatically shifted so that the type will never strike twice in the same place on the fabric. Another feature of the invention is embodied in a suitable support which may be used in place of the usual gripper bar.

35 Accordingly my invention is embodied in an attachment arranged and constructed as hereinafter set forth and as illustrated in the accompanying drawings in which—

Figure 1 illustrates in outline a portion of 40 a Gordon press equipped with the attachment.

Figure 2 is a side view of a portion of the platen and the attachment, showing the platen in sheet receiving position.

45 Figure 3 is a sectional view of parts of the attachment looking from the right in Figure 2.

Figure 4 is a view similar to Figure 2 but shows the platen in impression position.

Figure 5 is a detail view of parts of the 50 attachment looking from the left in Figure 4.

Figure 6 is a view in elevation of the 55 entire attachment mounted on the platen of the press, parts being broken away.

Without limiting the use of the invention to any particular type of press, the press herein illustrated is of the Gordon type or the type known as a Chandler & Price press. Referring to Figure 1, only so much of the 60 press is shown as is necessary to understand the invention. The press is identified by the framework 1 and the platen 2 which rocks on its pivots at 3. The platen is provided with two lugs 4 and 5 in which the 65 usual gripper bar (not shown) is pivoted. The cam 6 is pivoted to the platen at 7 and guides the gripper bar cam roll so as to maintain the usual platen grippers (not 70 shown) in their proper position with relation to the platen. The foregoing elements are all parts of the usual Gordon type press and require no further description.

Referring now to Figure 6, the numeral 75 10, denotes a base bar which is pivoted adjacent the edge of the platen in the aforesaid lugs 4 and 5. The bar 10 thus occupies a position on the press similar to the one of the usual gripper bar. The bar 10 has two 80 studs 11 and 12 which fit into the bearings 4 and 5. The upper portion of the base bar is provided with one or more slots 13 for adjustably attaching the frame pieces 14 and 15 by means of bolts 16. The frame pieces 85 have tongues 17 which fit into a groove 18 in the bar 10, and the groove is likewise adapted to receive the usual end tongues of the gripper. In other words, so far as described, the base bar 10 is identical with the usual 90 gripper bar. However, for purposes of the present invention, the base bar carries two depending arms 19, 19 and to one of these there is secured an arm 20 which carries a cam roll 21 which runs on the cam 6. The 95 positions and functions of the arm 20 and roll 21 are similar to the position and function of the well known like parts on the Gordon press.

The frame pieces 14 and 15 extend beyond the platen as seen in Figure 1 and at their upper free ends they are provided with suitable fittings 22, 22 adapted to receive a shade roller 23 between them. The shade roller carries a curtain spool 24 upon which is wound a curtain of suitable fabric 25, the lower end of which is detachably secured to a winding up roller 26 by suitable means 27 in the same manner in which a music roll may be mounted in a player piano. The curtain 25 is of suitable width with respect to the platen. The base bar 10 may be provided with suitable marks 28, 28 to enable the operator to position the frame pieces properly.

The winding up roller 26 is adjustably mounted on a shaft 30 by means of collars 31. One of the arms 19 is provided with a 20 slightly serrated bearing surface 32 and the shaft 30 carries a pin 33. The shaft is drawn to the left in Figure 6 with the pin 33 in contact with the serrated surface 32. It follows, that when the shaft is rotated, it 25 will at the same time have a slight axial reciprocating movement. If desired another collar 35 may be provided to insure the position of the shaft between the arms 19, 19.

30 The shaft 30 carries a pulley 36 and a spring 37 is interposed between the pulley and the arm 19 to draw the pin 33 against the serrations 32 as aforesaid.

Referring now more particularly to Figures 2 to 5, it will be seen that the base bar stud 11 projects outward from the platen lug 4 and carries, freely mounted thereon, a ratchet and pulley unit comprising a ratchet 40 and a pulley 41. Fixed to the stud 11 by a key 42 or other means is a pawl arm 43 which carries a pawl 44. A spring 45 keeps the pawl in engagement with the ratchet. The stud 11 further carries a cam 46 secured by a screw 47.

45 To the side of the lug 4 there is pivoted another pawl 48 having a pin 49 and which is kept in engagement with the ratchet 40 by a spring 50. A belt 51 passes over the pulleys 41 and 36. The pawl pin 49 extends outward into the path of the cam 46.

The operation is as follows: The normal position of the parts are as in Figure 2 with both pawls in engagement with the ratchet. As the platen now moves down into printing position, Figure 4, the pawl 48 will rotate the ratchet and pulley unit 40-41 a short predetermined distance. The length of the rotary movement is regulated by the position of the cam 46, in that, as the pawl 48 rotates with the platen lug 4, the pin 49 on said pawl will encounter the cam and the pawl therefore be lifted out of engagement with the ratchet.

55 The rotary movement of the ratchet and pulley unit 40-41 is transmitted to the

shaft 30 through the belt 51 and pulley 36, and as a result therefrom the winding up spool 26 is rotated a short distance thereby shifting the fabric 25 so that the impact surface of the fabric between the type and the platen is automatically shifted or changed lengthwise for every stroke of the press. At the same time the fabric is also given a slight crosswise or lateral movement because of the cooperation of the pin 33 with the serrated bearing at 32.

On the opening stroke of the press, from the position in Figure 4 to the position in Figure 2, the ratchet and pulley unit 40-41 remain stationary due to the pawl 44, and the pawl 48 slides off the cam 46 and again engages the ratchet ready for the next operation. When the sheet has been entirely unwound from the shade roller, it may be removed and wound up again for further use as is obvious.

From the foregoing it is clear that this invention provides an attachment by means of which a sheet of fabric is positioned on the press for facsimile printing purposes in which the fabric is automatically shifted for every impression.

When the attachment is not used, it may be easily disassembled by removing the belt 51 and pin 33 to slide the shaft 30 through its bearings in the arms 19. Also by removing the frames 14 and 15 with the shade roller.

Thereafter the regular platen grippers may be mounted in the usual manner on the base bar 10. By loosening the screw 47, the cam 46 may be adjusted to regulate the operating stroke of the pawl 48.

The foregoing is believed to disclose this invention in its complete preferred form. Nevertheless, it will be understood that the invention is not limited to the precise detailed construction presented, but that changes or alterations may be made without departing from the principle of the invention and the scope of the appended claims.

I claim:

1. The combination with a platen press having lugs adapted to receive a gripper bar, of an attachment of the character described comprising a base bar mounted to oscillate in said gripper bar lugs, frame members adjustably mounted in said base bar, and projecting upwardly therefrom, an upper roller mounted in the extreme free upper ends of said upright frame members, a lower roller mounted on said base bar, a sheet of fabric wound upon said roller and means carried by said base bar and one of the said gripper bar lugs for operating the said sheet of fabric across the platen of the press.

2. The combination with a platen press having lugs mounted thereon at each of the lower corners of the platen, of an attach-

ment therefore comprising a base bar and lugs for operating said sheet of fabric pivoted in said lugs adjacent the lower edge of the platen, upright supporting members mounted on said base bar, fabric carrying rollers on said supporting members and base bar, a sheet of fabric wound on said rollers, from one roller to the other roller and means on one of the said base bar pivots on said base bar adapted to cooperate with 10 maintaining said base bar in predetermined operative relationship with the said platen. 5

S. HAINES PLUM, 2d.
